J. W. MOORE

JACK

Filed April 8, 1922

By *Cadwallader*.
Attorney.

UNITED STATES PATENT OFFICE.

JOHN WALTON MOORE, OF ROANOKE, WEST VIRGINIA.

JACK.

Application filed April 8, 1922. Serial No. 550,592.

To all whom it may concern:

Be it known that I, JOHN W. MOORE, a citizen of the United States, residing at Roanoke, in the county of Lewis and State 5 of West Virginia, have invented a new and useful Jack, of which the following is a specification.

The device forming the subject matter of this application is a lifting jack of that general type in which the screw does not 10 rotate, rotation being imparted to a nut which is threaded on the screw.

The invention aims to provide a novel means for rotating the nut, to provide novel 15 means for holding the constituent parts of the jack together, to provide a jack which will operate antifrictionally and be accessible in places where room is limited, and, generally, to improve and to enhance the 20 utility of devices of that type to which the invention appertains.

With the above and other objects in view, which will appear as the description proceeds, the invention resides in the combination 25 and arrangement of parts and in the details of construction hereinafter described and claimed, it being understood that, within the scope of what is claimed, changes in the precise embodiment of the invention 30 shown can be made without departing from the spirit of the invention.

In the accompanying drawings:—

Figure 1 shows in elevation, a jack constructed in accordance with the invention; 35 Figure 2 is a longitudinal section wherein parts appear in elevation; Figure 3 is a section on the line 3—3 of Figure 1; Figure 4 is a section on the line 4—4 of Figure 2; Figure 5 is a section on the line 5—5 of 40 Figure 2.

The device forming the subject matter of this application includes a base 1 provided at its upper end with a reduced neck 2 defining a shoulder 3. A ball race 4 is formed 45 in the upper end of the neck 2. There is a chamber 5 in the lower end of the base 1, the base being provided with a reduced bore 6, extended upwardly from the chamber 5 through the neck 2.

A nut 7 is disposed above the neck 2 and is provided in its lower edge with a ball race 8 cooperating with the ball race 4 in the neck 2 of the base 1. Balls 9 are disposed in the ball races 8 and 4. At its lower end, the 55 nut 7 has an outwardly extended flange 10.

A retaining sleeve 11 is threaded on the neck 2 and is provided at its upper end with an inwardly extended flange 12, overhanging the flange 10 on the nut 7, to hold the nut on the base 1 for rotation. The nut 7 is provided with a ratchet 14 having teeth so constructed that, through the instrumentality of a reversible pawl, hereinafter described, rotation may be imparted to the nut 7 in opposite directions.

A collar 15 surrounds the ratchet 14 of the nut 7 and is supported on the upper end of the sleeve 11, the collar having a tubular extension 16 adapted to receive the inner end of a detachable handle 17. The collar 15 has an outwardly extended boss 18 provided with a transverse groove or seat 19 in its outer end. A compartment 20 is formed in the collar 15 and in the boss 18, there being a reduced bore 21 in the outer end of the 75 boss, the bore communicating with the compartment 20. The device includes a pawl comprising a head 22 slidable in the compartment 20, and a reduced stem 23 slidable in the reduced bore 21, the head 22 coacting 80 with the ratchet 14 on the nut 7 and being beveled as indicated at 24. A compression spring 25 surrounds a portion of the stem 23 of the pawl and is located in the compartment 20, one end of the spring abutting 85 against the end 22 of the pawl, and the other end of the spring 25 abutting against the boss 18 at the outer end of the compartment 20. The pawl includes a grip whereby the pawl may be manipulated on occasion. The 90 grip may be in the form of a nut 26, having wings 27. The nut is threaded on the stem 23 of the pawl and is held thereon by upsetting the threads on the stem of the pawl, or in any other suitable way. The function of 95 the grip on the pawl will be explained hereinafter, but it is to be observed at this place that a simple wing nut is used in making the grip.

A collar 28 surrounds the upper end of 100 the nut 2 and constitutes means for holding the collar 15 on the nut for rotation. The collar 28 has oppositely disposed openings 29 communicating with an internal groove 30 in the collar. The internal groove 30 in the collar 28 cooperates with an external groove 31 on the nut 7. A securing element 32 which may be a cotter pin, is mounted in the openings 29 of the collar 28 and in the groove 30 of the collar and in the 110

groove 31 of the nut 7, the cotter pin or its equivalent constituting means for holding the collar on the nut.

A screw 33 is threaded into the nut 7 and extends downwardly through the bore 6 of the base 1 into the chamber 5 in the base. At its upper edge, the screw 33 is supplied with a head 34 which may be rigidly mounted on the screw.

10 In practical operation, rotation is imparted to the nut 7 through the instrumentality of the ratchet 14, the pawl 22—23, the collar 15 and the handle 17. When the nut 7 is rotated, the screw 33 moves upwardly, without turning, the load on the head 34 of the screw holding the screw against rotation. When the collar 15 is rotated reversely, to enable the pawl 22—23 to secure a new hold on the ratchet 14 of 20 the nut 7, the beveled end 24 of the pawl clicks over the ratchet, the spring 25 constituting means for advancing the pawl, and the wings 27 on the grip or nut 26 sliding in the groove or seat which is formed in the 25 outer end of the boss 18 on the collar 15. Through the instrumentality of the grip 26, the pawl 22—23 may be retracted and rotated, to effect a reversal of the pawl, the wings 27 on the grip being permitted to re-enter the groove 19. When the pawl has 30 been reversed, as above explained, a swinging movement of the lever 17 will impart reverse rotation to the nut 7, and the screw 33 will be lowered.

35 What is claimed is:—

1. In a device of the class described, a base provided with a bore and having a reduced neck defining a shoulder; a sleeve mounted on the neck and cooperating with the shoulder, the sleeve having an inwardly extended flange; a nut supported for rotation on the neck and provided with an outwardly extended flange engaged beneath the flange of the sleeve, the nut having a ratchet; a collar

surrounding the ratchet and supported for 45 rotation on the sleeve; means for rotating the collar; a pawl carried by the collar and cooperating with the ratchet; a ring on the upper end of the nut and constituting means for holding the collar in place for rotation, 50 the ring being provided with openings and having an internal groove disposed between the openings, the nut having an external groove cooperating with the internal groove of the ring; a fastening element engaged in the openings and in the grooves; and a screw threaded into the nut and extended 55 downwardly into the bore of the base.

2. In a device of the class described, a base; a nut rotatable on the base and provided with a ratchet; a screw threaded into the nut; a collar surrounding the ratchet and having an external seat; and an axially reversible spring-actuated pawl carried by the collar and cooperating with the ratchet, the pawl having a wing adapted 60 to be received in the seat to hold the pawl against rotation on its axis.

3. In a device of the class described, a base, a nut rotatable on the base and provided with a ratchet, a screw threaded into the nut, a collar surrounding the ratchet and having oppositely disposed external seats, an axially reversible spring-actuated pawl carried by the collar and cooperating with 70 the ratchet, and a wing nut inverted upon the pawl and held thereon, the wing nut comprising a body and oppositely disposed wings, the wings coacting with the seats of the collar.

75 In testimony that I claim the foregoing as my own, I have hereto affixed by signature in the presence of two witnesses.

JOHN WALTON MOORE.
